REFRIGERATION APPARATUS

Carl Buhler, Springfield, Mass., assignor to Westinghouse Electric & Manufacturing Company, East Pittsburgh, Pa., a corporation of Pennsylvania

Application June 23, 1942, Serial No. 448,088

6 Claims. (Cl. 62—1)

This invention relates to refrigeration apparatus and more particularly to a means for defrosting the cooling unit of such apparatus.

It is an object of the invention to provide novel means for defrosting the cooling unit of refrigerating apparatus.

Another object of the invention is to provide means to selectively defrost portions of the cooling unit.

A further object of the invention is to defrost the cooling unit of refrigerating apparatus without materially raising the temperature of materials in or near the cooling unit.

These and other objects are effected by my invention as will be apparent from the following description and claims taken in accordance with the accompanying drawing, forming a part of this application, in which:

Fig. 1 is an elevation of the upper portion of a domestic refrigerator with the door removed to show the cooling unit and the defrosting device of this invention;

Fig. 2 is an enlarged side elevation of the evaporator and defrosting device of Fig. 1; and,

Fig. 3 is an enlarged sectional view of the defrosting device taken substantially on the line III—III of Fig. 2.

Referring to the drawing for a description of the invention, the reference numeral 10 designates the insulated walls of a domestic refrigerator cabinet. An evaporator 11 is secured to the lower surface of the upper wall of said cabinet. The evaporator 11 comprises two U-shaped sheets of metal 16 and 17 which form a base 12 and two legs 13 and 14.

Depressions are formed in sheet 16 to provide two refrigerant headers 18 and 19. Further depressions are also formed to provide a plurality of parallel refrigerant passages 21, each of which communicates with both of the headers 18 and 19 and run vertically downward on the legs 13 and 14 and horizontally across the base 12. In the central portion of the base, the passages 21 are joined by a cross passage 22. Horizontal cross passages 23 and 24 are also provided on each of the legs 13 and 14 of the evaporator 11, which passages afford cross communication between the passages 21.

The evaporator 11 also includes a metal shelf 26 secured in the interior of the U-shaped evaporator 11. The shelf 26 is likewise composed of two sheets of metal 27 and 28 in which depressions are formed to provide a refrigerant passage 29. The shelf 26 divides the evaporator into a lower compartment 30 and an upper com-

- partment 34, the latter being used primarily for the storage of frozen foods.
- 5 The shelf 26 is supplied through the tube 31 with refrigerant liquid from a compressor-condenser unit (not shown). The refrigerant liquid and vapor in the shelf 26 discharges through a tube 32 to one end of the cross passage 22 from where it passes into the passages 21. The refrigerant liquid vaporizes in the evaporator 11 including the shelf 26 and the refrigerant vapor flows into the two headers 18 and 19 from which it is withdrawn through a suction tube 33 by the above-mentioned compressor-condenser unit. The compressor-condenser unit is controlled by 15 a switch (not shown) responsive to the temperature of the refrigerator cabinet in a manner well known in the art. The normal refrigerant liquid level 46 in the evaporator is above the passages 23 and 24.
- 10 The defrosting device of this invention comprises a cylindrical chamber 36 having an axial tube 37 in which an electric heating element 38 is located. The heating element 38 is removable and has a supporting collar 40 secured to it 15 which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion 20 of the chamber 36 with the cross passage 22. The heater 38 is energized through two leads 43, in one of which a controlling switch 44 is located.
- 25 Switch 44 is normally open during the operation of the evaporator 11, and during such operation, frost will collect on the surfaces of the evaporator 11. When the evaporator 11 is to be defrosted, the supply of refrigerant liquid 25 and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 30 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 35 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 40 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 45 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 50 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.
- 55 The defrosting device of this invention comprises a cylindrical chamber 36 having an axial tube 37 in which an electric heating element 38 is located. The heating element 38 is removable and has a supporting collar 40 secured to it which engages the upper surface of the chamber 36. A conduit 39 connects the upper portion of the chamber 36 with the cross passage 24 and another similar conduit 41 connects the upper portion of the chamber 36 with the cross passage 23. A third conduit 42 connects the lower portion of the chamber 36 with the cross passage 22. The heater 38 is energized through two leads 43, in one of which a controlling switch 44 is located.

quickly melt the frost on the walls of the evaporator 11. After the frost has melted, switch 44 is opened and the flow of refrigerant liquid through the tube 31 is re-established.

It will be observed that the circulation of warm refrigerant liquid effected by the energization of the heater 38 cannot flow through the passage 29 in the shelf 26, so that the shelf 26 is not defrosted. Frozen comestibles on the shelf 26, therefore, will not be melted during the defrosting operation.

It will be apparent from the above that this invention provides a novel means for quickly defrosting a cooling unit. It also provides a novel means for selectively defrosting certain portions of a cooling unit containing a refrigerant liquid, so that comestibles in contact with other portions of the cooling unit are not melted.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a cooling unit having refrigerant passages therein, a chamber adapted to be heated, at least one duct communicating with said chamber and said passages, said chamber and passages being adapted to contain a refrigerant liquid, said duct and chamber being so located with respect to said passages that when said chamber is heated, warm refrigerant liquid will circulate through said chamber and only a portion of the refrigerant passages of the cooling unit, whereby frost which may have accumulated on said cooling unit, is melted substantially only from the portion of the cooling unit containing the passages through which the warm refrigerant liquid from the chamber is circulated.

2. In a cooling unit providing two refrigerated compartments, refrigerant passages in the walls of each of said compartments, a chamber, said passages and chamber being adapted to contain a refrigerant liquid, means for supplying a refrigerant liquid for said passages and chamber, means for heating said chamber, at least one duct communicating with said chamber and with the refrigerant passages in the walls of one of said compartments in such a manner that when the supply of refrigerant liquid to said cooling unit is stopped and the chamber heated, warm refrigerant liquid will circulate successively through the chamber and through the refrigerant passages in the walls of said one compartment to melt the frost which may have formed thereon.

3. A cooling unit for a refrigerator having an

insulated cabinet, said cooling unit comprising a U-shaped member having refrigerant passages in at least one side and bottom wall, a shelf in said U-shaped member having refrigerant pas-

5 sages therein, means for circulating a refrigerant liquid through all of said passages, a chamber communicating with the passages of the U-shaped member, refrigerant liquid in said chamber, means for heating said chamber, the communication of said chamber with said U-shaped member being such that when said chamber is heated, relatively warm refrigerant liquid from said chamber will circulate through the passages of the U-shaped member and not through the refrigerant passages of said shelf.

10 4. In a cooling unit comprising two refrigerant containing portions, a chamber adapted to contain refrigerant liquid, means for supplying a refrigerant liquid to the said portions and to said chamber, means for heating said chamber, at least one duct communicating with said chamber and with one of said portions in such a manner that when the supply of refrigerant liquid to said cooling unit is stopped and the chamber heated, warm refrigerant liquid will circulate successively through the chamber and through said one portion to melt the frost which may have formed thereon, the other of said portions being unaffected by said warm refrigerant liquid.

15 5. A cooling unit for a refrigerator including an insulated cabinet, said cooling unit comprising a U-shaped member having refrigerant passages in at least one side and bottom wall, a shelf in said U-shaped member having refrigerant passages therein, means for circulating a refrigerant liquid through all of said passages, a refrigerant conduit connected in parallel with only the refrigerant passages in said U-shaped member, said conduit including a chamber, said chamber being positioned below the refrigerant liquid level in

20 said U-shaped member, and means for heating the refrigerant liquid in said chamber whereby said heated refrigerant liquid will circulate only through said conduit and through the refrigerant passages of said U-shaped member.

25 6. A cooling unit having a refrigerant passage comprising a first portion and a second portion connected in series, means for conducting a refrigerant liquid through said passage, a conduit in parallel with said second portion of said passage, said conduit including a chamber located below at least the upper portion of the refrigerant liquid in said second portion, said chamber containing refrigerant liquid, and means for heating the refrigerant liquid in said chamber whereby said heated refrigerant liquid circulates through said second portion but not through the first portion of said passage.

CARL BUHLER.
